UNITED STATES PATENT OFFICE

ROSS H. FORNEY, OF DALLAS, TEXAS, ASSIGNOR TO FORNEY COMBUSTION ENGINEERING COMPANY, OF DALLAS, TEXAS, A CORPORATION OF TEXAS

OIL AND STEAM BURNER NOZZLE

Application filed April 1, 1929. Serial No. 351,576.

This invention relates to new and useful improvements in oil and steam burner nozzles.

One object of the invention is to provide an oil and steam burner nozzle including improved means for bringing about a more efficient atomization of the oil by the steam.

A further object of the invention is to provide a nozzle whereby the oil and steam will be atomized in a conical spray so as to produce a wide spread conical flame.

Another object of the invention is to discharge the oil in a continuous annular path directly into a projected cone of steam, whereby a more thorough and even distribution and commingling is carried out.

A still further object of the invention is to provide a nozzle in which all the parts may be readily disconnected for cleaning and inspection.

A construction designed to carry out the invention will be hereinafter described, together with other features of the invention.

The invention will be more readily understood from a reading of the following specification and by reference to the accompanying drawings in which an example of the invention is shown, and wherein:

Fig. 1 is a longitudinal sectional view of a nozzle constructed in accordance with the invention.

Fig. 2 is a transverse sectional view taken on the line 2—2 of Fig. 1.

Fig. 3 is a similar view taken on the line 3—3 of Fig. 1, and

Fig. 4 is a transverse sectional view taken on the line 4—4 of Fig. 1.

In the drawings the numeral 10 designates a steam tube to which steam or other pressure fluid such as compressed air is suitably supplied. An oil or fuel tube 11, much less in diameter, is concentrically mounted in the steam tube and is suitably supplied with oil or the like.

An adapter 12 is formed with a shoulder screw-threaded shank 13 which is screwed into the end of the tube 10 so that the latter abuts the shoulder 14. The adapter has an axial nipple 15 extending rearwardly into the tube 10 and provided with internal screw

threads for receiving the forward end of the oil tube 11. The adapter is not only rigidly mounted in the forward ends of the steam and oil tubes, but serves to hold them securely in their relative positions.

The adapter also has an axial bore 16 which is internally screw-threaded for receiving the stem 17 of a nozzle head 18. The stem has a central duct 19 communicating through a reduced orifice 20 with intersecting radial ports 21 located in an annular collar 22 which forms a shoulder for the stem.

The adapter 12 has an enlarged collar 23 projecting beyond the tube 10 and provided at its front edge with opposite annular bevels 24 and 25, respectively. A frusto-conical spreader 26 is confined on the stem against the adapter by the collar 22 and extends from the collar 23. The inner bevel 24 concentrically surrounds the spreader and is spaced slightly therefrom to provide a forwardly flaring annular slot 27 therebetween, through which the steam is discharged in a conical spray.

The adapter has longitudinal steam ducts or passages 28 receiving steam from the tube 10 and discharging it within the collar 23 so as to impinge the outer surface of the conical spreader 26. The steam is discharged through the narrow annular slot 27 in a thin flaring or conical spray. The outer annular bevel 25 provides a cut back surface which gives clearance to the steam spray.

The spreader 26 overhangs the ports 21 and oil from the tube 11 is conducted through the shank 15, duct 19 to the orifice 20. The reduced orifice regulates the quantity of oil delivered to the ports 21. The oil discharged from the ports strikes the inner conical surface of the spreader and is deflected into the annular sump 29 which surrounds the collar 22 in the head 18, whereby the oil is spread and distributed.

The head is of greater diameter than the adapter collar 23 and the spreader 26 and has an annular beveled face 30 flush with the outer surface of the spreader and of the same pitch. The forward edge of the spreader is spaced sufficiently from the head to form a narrow annular slot 31 and the oil spread

into the sump 29 is discharged through this slot into the path of the steam spray. To reduce the radial width of the slot 31 the spreader is provided with an inner annular bevel 32.

It will be seen that the oil is discharged substantially transversely of the path of the steam and therefore will be atomized by the latter. The forward flare of the spreader 10 and the face 30 of the head will cause the steam atomized oil spray to spread in a widely amplified conical form which is highly desirable for boiler furnaces.

Further the oil and steam will be thoroughly commingled and a highly combustible fuel will be delivered by the nozzle. The slots 27 and 31 are very narrow and are restricted to the discharge of thin annular sheets of steam and oil. It is obvious that 20 by removing the head 18 and stem 17 the spreader 26 may be taken out and the nozzle easily cleaned.

Various changes in the size and shape of the different parts, as well as modifications 25 and alterations, may be made within the scope of the appended claims.

What I claim, is:

1. In a combined fuel nozzle, a steam tube, a fuel tube extending longitudinally within 30 the steam tube, a circular member at the outer end of the steam tube, a conical spreader within the circular member providing an annular steam discharge opening therebetween, and a head having a fuel passage connected 35 with the fuel tube and an annular outer portion bevelled and flush with the outer surface of the spreader, the outer end of the spreader being spaced from the head to provide a restricted annular discharge opening for the 40 fuel fluid.

2. In a combined fuel nozzle, a steam tube, a fuel tube extending longitudinally within the steam tube, an adapter connected to the end of the steam tube and having a flared 45 steam outlet, a head having a reduced shank mounted in the adapter and provided with fuel passages connected with the fuel tube, and a conical spreader fitting in the flared discharge opening of the adapter, the head 50 overhanging the spreader and providing therewith an annular fuel discharge slot, the head having undercut surfaces for deflecting the fuel from the passage to said slot.

3. A fuel nozzle as set forth in claim 2, in 55 which the adapter is provided with longitudinal steam ducts between the steam tube and the flared discharge opening, and also in which the head has a bevelled outer surface contiguous to and flush with the outer 60 surface of the spreader and extending outwardly of the fuel discharge opening.

4. In a combined fuel nozzle, a tubular pressure fluid conductor, a fuel conductor extending longitudinally within the pressure 65 fluid conductor, an adapter connected to the

end of the pressure fluid conductor and extending axially thereof, a head disposed concentrically of the adapter and the fuel conductor and connected with the fuel conductor, means at the adapter and the head for 70 directing the fuel fluid radially and constructed so as to direct said fluid outwardly in an unobstructed plane, and means co-acting with the adapter and head constructed for atomizing the pressure fluid forwardly 75 in an inverted cone form and involving the fuel fluid at its point of ejection from the head.

In testimony whereof I affix my signature.

ROSS H. FORNEY.
